PAPER FEED DEVICE

George W. Wender, United States Army,
Camp Ritchie, Md.

Application October 17, 1944, Serial No. 559,111

8 Claims. (Cl. 271—42)

(Granted under the act of March 3, 1883, as
amended April 30, 1928; 370 O. G. 757)

The invention described herein, if patented may be manufactured and used by or for the Government for governmental purposes, without the payment to me of any royalty thereon.

This invention relates to a Mimeograph machine, and more particularly to an improved feeding device for feeding impression paper to the printing or stenciling cylinders of the machine.

In existing mimeographing machines, the impression paper sheets are fed to the printing and impression cylinders by a feeding pad which is reciprocated to engage the upper surface of the uppermost sheet of a stack of paper and propel the sheet to the bight of the printing and impression cylinders. When paper of low quality is employed, the movement of the feeder pad relative to the exposed sheet surface produces an excessive quantity of lint which is deposited on the upper surface of the uppermost sheet of paper. This lint is subsequently deposited on the stencil in its printing area, thereby seriously affecting the quality of work produced by the machine.

It is, therefore, an object of this invention to provide an improved paper feeding device for application to conventional Mimeograph machines.

A further object of the invention is to provide an improved paper feeding device for application to a Mimeograph machine, the device being constructed and arranged to operably engage the marginal portion of the uppermost sheets of a stack of paper and propel the sheet to the printing cylinders.

A specific object of the invention is to provide a feeding device for application to a Mimeograph machine, the device being constructed and arranged for accurate adjustment so that its components which engage the sheet to be printed or stencilled may be adjusted in conformity with the width of the sheet to insure that the sheet is engaged only in its marginal areas by the feeding components of the device.

A more specific object of this invention is to provide an improved paper feeding device for application to a Mimeograph machine, the device being constructed and arranged for expeditious attachment to the conventional feed head carried by the feed pad rocker arm of the machine, and also constructed and arranged for convenient adjustment relative to the width of the sheet of paper to be printed or stencilled in order that the feeding pads of the device engage the sheet in its marginal areas.

It is also an object of this invention to provide for use in a Mimeograph machine a paper feed attachment of generally improved construction, whereby the device will be simple, durable, and inexpensive in construction, as well as convenient, practical, serviceable, and efficient in its use.

With the foregoing and other objects in view which will appear as the description proceeds, the invention resides in the combination and arrangement of parts and in the details of construction hereinafter described and claimed, it being understood that various changes in form proportion, and minor details of construction may be made within the scope of the claims without departing from the spirit or sacrificing any advantages of the invention.

For a complete disclosure of the invention, a detailed description thereof will now be given in connection with the drawings forming a part of the specifications, wherein:

Figure 1 is a side elevational view of a conventional Mimeograph machine showing my invention applied thereto;

Figure 2 is a transverse section taken on the line 2—2 of Figure 1;

Figure 3 is a top plan view of the feed bar and feed which may be employed in practicing this invention.

Figure 4 is a transverse sectional view of the improved feed device taken on the line 4—4 of Figure 2.

Figure 5 is an end elevation view, partly in section, of a modified paper feeding device; and

Figure 6 is a fragmentary top plan view of Figure 5.

Referring to the drawings, in which corresponding parts are indicated by similar reference characters, 10 indicates a conventional Mimeograph machine of the type manufactured by A. B. Dick Company and known as Model 100. This machine includes a printing or stencilling cylinder 11 and a co-operating impression cylinder 12. A feed table 13 is provided, and a stack of sheets of impression paper P is located on the feed table

13 and each sheet is guided to the co-operating stencilling cylinders 11 and 12 by an elongated side gauge 14, which engages one edge of each sheet of paper, and the opposed edge of each sheet is yieldably engaged by side guides 15 and 16 which are biased for movement towards the elongated side gauge 14.

In the conventional Mimeograph machine, the impression paper P is fed to the stencilling cylinders 11 and 12 by a rubber feed pad, not shown, which is supported by the conventional feed head

17. This head 17 is supported at the outer terminal of a feed arm 18 which is secured to and supported by the conventional feed pad rocker bar 20, that is mounted for oscillatory movement on the upper feed arm 21, in conformity with the usual practice. The feed head 17 is operated for reciprocatory and oscillatory movement in conformity with usual practice, which is well understood by those skilled in the art, as will be more fully explained hereinafter.

The mechanism for operating the feed head 17 and rocker bar 20 is well known to those skilled in the art, consequently it has not been illustrated in this application.

The feed head 17 includes a rectangular body plate 23 having opposed downwardly disposed and transversely-extending flanges 25 of conventional construction. A locking lug 26 extends downwardly from the plate 23 at a point intermediate the flanges 25, and this lug is provided with an elongated transversely-extending recess 27 for the reception of a locking ear to be hereinafter disclosed. A locking pin 30 is slidably mounted in axially-aligned cylindrical recesses 31 formed in the locking lug 26. The locking pin 30 has an annular groove 32 formed in its peripheral portion, and a stop ring 33 is also secured to the peripheral portion of the locking pin 30 to limit the outward movement of the pin. The stop ring 33 is normally held in engagement with an outer surface of the locking lug 26 by a leaf spring 35. The opposed terminals of the leaf spring 35 engage the inner face of a flange 25, and its intermediate portion yieldably engages the inner terminal of the locking pin 30, thereby biasing the pin for outward movement, which movement is limited by the engagement by the stop ring 33 with the outer surface of locking lug 26. The components hereinbefore defined are of conventional construction and arrangement.

The improved paper feed attachment forming the subject matter of this invention is adapted to replace the conventional rubber feed pads, and this improved feeder includes a feed bar or beam 40 which is preferably formed of channel material provided with laterally-projecting flanges 41 and 42 that extend longitudinally along the edges of the bar to define a channel 43 therebetween. Aligned elongated slots 44 are formed in the feeder bar 40 adjacent its opposed terminals, and the intermediate portion of the bar 40 has a U-shaped attaching bracket 45 secured thereto by attaching flanges 46 which extend therefrom and which are welded or otherwise secured to the bar 40. A strip or plate 47 is secured to the intermediate portion of the securing bracket 45, and this plate has an attaching ear 48 which extends perpendicularly therefrom. The ear 48 has a circular aperture 50 formed therein which is interrupted by a restricted recess 51 that extends outwardly through the attaching ear from the circular aperture 50. The attaching ear 48 may be secured in any preferred manner to the plate 47, and in the arrangement here depicted the ear is provided with a perpendicularly-extending flange 52, which is welded or otherwise secured to the upper surface of the plate 47.

The attaching ear 48 is similar in construction and performs the same function as the conventional attaching ear which is carried by the conventional rubber feed pad, not shown. In the conventional arrangement the rubber feed pad is secured to the conventional feed head 17, in the manner in which this feed attachment is secured to the head 17, as will be hereinafter

disclosed. Feed legs 53 are provided, and each leg has a perpendicularly-extending flange 55 formed at one terminal, and this flange is received within the channel 43 of the bar 40. Each flange 55 has a threaded aperture 56 formed therein for the reception of the threaded shank of a machine screw 57. The shank of each machine screw 57 is received within one of the elongated slots 44 of the bar 40, and when the machine screw 57 is tightened its enlarged head engages the outer surface of the bar 40, thereby securely binding the feed leg 53 to the bar. Inasmuch as the flange 55 of each leg 53 is snugly received within the channel 43 of the bar 40, each leg is held against rotary motion relative to the bar 40.

Each leg 53 is provided with a perpendicularly-disposed feed foot 60 which has a rubber feed pad 61 bonded or otherwise suitably secured to its outer or lower surface. Each feed foot and feed pad is of rectangular configuration, and their length is disposed transversely with relation to the bar 40. By this arrangement the feed legs 53 may be conveniently and accurately adjusted by manipulating the adjusting screws 57 so that the feed pads engage the marginal areas of the impression sheet.

In order to secure the improved feed device to the feed head 17, the locking pin 30 is pressed 30 inwardly against the tension of the spring 35 so that its annular groove 32 aligns with the recess 27 formed within the lug 26. With the locking pin in this position, the securing ear 48 is positioned within the recess 27 with its circular aperture 50 in axial alignment with the pin 30. Now the pin is released and the spring 35 moves it longitudinally outward, thus moving the body of the pin 30 into the circular recess 50. This locks the improved feed device to the feed head 17, and inasmuch as the feed legs 53 have been adjusted causing the feed pads 61 to engage the marginal portions of the impression sheet, it is manifest that the printing or stenciling area of the sheet will not be engaged by the feeder pad 61.

If impression paper of low quality is being fed to the printing or stenciling cylinders, the operation of the feed device may cause the feed pads 61 to create paper lint. This lint, however, only engages the marginal portion of the sheet, thus leaving its printing or stenciling area substantially free of the lint so that the stencil impressions remain clear and well defined.

By substituting this improved paper feed device for the conventional rubber feed pad, it is manifest that well defined characters may be stenciled on the impression sheet and that accurate register be maintained, because no appreciable quantity of lint is produced or deposited in the impression area of the impression sheet.

60 A modified form of my invention is disclosed in Figures 5 and 6. This device includes a bar or beam 40a which has an attaching ear 48a secured to the top portion of the bar 40a; this attaching ear is similar in construction and arrangement and performs the same function as the attaching ear 48 hereinbefore disclosed. Feed legs 53a are provided, each leg having a perpendicularly-extending flange 55a formed at one terminal, said flanges having laterally-projecting flanges 55b and 55c that extend longitudinally along the edges of the flange 55a to define the channel 55d therebetween. The legs 53a are adjustably secured to the bar 40a by machine screws 57a, the shank of each machine screw 57a being received within one of the elongated slots 44a

formed in the flange 55a, and threaded portion of the screw being received in the threaded apertures 56a formed in the bar 40a. Each leg 53a is provided with a feed foot 60a and a feed pad 61a is secured to the lower face of each feed foot 60a.

This form of the feeding device may be readily secured to the feed head 17 by inserting the attaching ear 48a in the recess 27 of the feed head 17. When the bar 40a is secured to the feed head 17 its feed legs 53a are adjusted to locate the feed pads 61a to engage the marginal area of the impression sheet to be stenciled or printed.

Having thus described my invention, what I claim as new and useful is:

1. In a Mimeograph machine, the combination with cooperable stenciling cylinders, a feed table, a feed rocker arm, a feed head carried by the said rocker arm, an attaching lug carried by the feed head and having a recess formed therein, a locking pin axially slidable within the recess, of a unitary bar, a securing ear carried by the bar and having an aperture formed therein and adapted to receive the locking pin to secure the bar to the feed head, spaced resilient feed pads secured at the outer terminals of the feed bar and located to spacedly and frictionally engage the marginal portions of a sheet of impression paper supported on the feed table to feed the sheet from the table to the stenciling cylinders of the machine.

2. In a Mimeograph machine, the combination with cooperable stenciling cylinders, a feed table, a feed rocker arm, a feed head carried by the said rocker arm, an attaching lug carried by the feed head and having a recess formed therein, a locking pin axially slidable within the recess, of a unitary bar, a securing ear carried by the bar and having an aperture formed therein adapted to receive the locking pin to secure the bar to the feed head, feed legs adjustably secured to the feed bar, a spaced resilient feed pad carried at the lower terminal of each feed leg and located to spacedly and frictionally engage the marginal portion of a sheet of impression paper supported on the feed table to feed the sheet from the table to the stenciling cylinders of the machine.

3. A paper feed device for use in a Mimeograph machine having cooperable stenciling cylinders and a feed component, the device including a unitary bar, spaced resilient feeder pads supported at the outer terminals of the bar and

adapted to spacedly and frictionally engage the marginal portion of a sheet of paper to feed the paper to the stenciling cylinders, and a securing ear carried by the bar and adapted to be secured to the said feed component.

4. A paper feed device for use in a Mimeograph machine having cooperable stenciling cylinders and a feed component, the device including a unitary bar, feed legs adjustably secured to the terminals of the bar, spaced resilient feed pads supported at the lower terminal of the feed legs and adapted to spacedly and frictionally engage the marginal portions of a sheet of paper to feed the paper to the stenciling cylinders, and a securing ear carried by the bar and adapted to be secured to the said component.

5. A paper feed device for use in a Mimeograph machine having cooperable stenciling cylinders and a feed component, the device including a bar, feed pads supported at the outer terminals of the bar and adapted to engage the marginal portions of a sheet of paper to feed the paper to the stenciling cylinders, an attaching bracket carried by the bar, a securing ear carried by the attaching bracket and adapted to be secured to the feed component.

6. A paper feed device for use in a Mimeograph machine having cooperable stenciling cylinders and a feed component, the device including a bar, feed legs adjustably secured to the terminals of the bar, feed pads supported at the lower terminal of the feed legs and adapted to engage the marginal portions of a sheet of paper to feed the paper to the stenciling cylinders, an attaching bracket carried by the bar, a securing ear carried by the attaching bracket and adapted to be secured to the feed component.

7. In a paper feed device for use in a Mimeograph machine and including a feed bar, an attaching bracket supported by the feed bar, an attaching ear supported by the bracket, feed pads supported at the outer terminals of the feed bar and located to engage the marginal portions of a sheet of impression paper.

8. In a paper feed device for use in a Mimeograph machine and including a feed bar, an attaching bracket supported by the feed bar, an attaching ear supported by the bracket, feed legs adjustably secured to the terminals of the feed bar, and feed pads secured to the lower terminals of the feed legs and located to engage the marginal portions of a sheet of impression paper.

GEORGE W. WENDER.
